H. W. Stackpole

Attorney

UNITED STATES PATENT OFFICE.

ERNEST H. CARLSON, OF CLAY CENTER, KANSAS.

TRACTOR-FLOW ADJUSTMENT LEVER.

Application filed June 12, 1922. Serial No. 567,686.

To all whom it may concern:

Be it known that I, ERNEST H. CARLSON, a citizen of the United States, residing on R. F. D. No. 1, Clay Center, in the county of 5 Clay and State of Kansas, have invented certain new and useful Improvements in Tractor-Plow Adjustment Levers, of which the following is a specification, reference being had to the accompanying drawing, 10 which is made a part hereof.

My invention relates to appliances for regulating the depth of plows in gangs, particularly what is known as the Oliver type of tractor plow, for use with tractors and 15 the principal object thereof is to increase the range of adjustment of the plows by means of the lever and avoid to a large extent having to remove and replace bolts and blocks in the process of adjustment as is required in the operation of some plows now 20 in use.

I attain this object by means of the device hereinafter described and illustrated by the accompanying drawing, in which,—

25 Figure 1 is a view of a side elevation of the link connection;

Fig. 2, a plan view of same;

Fig. 3, a sectional view on line 3—3 of Fig. 1;

30 Fig. 4, a sectional view on line 4—4 of Fig. 1.

Similar numerals of reference indicate like parts thruout the several views.

The main frame 1, stub axle 2, wheel 3, 35 operating lever 4, segment 5, securing bolt 6, pivot 7, operating link 12, pivots 13 and 14, casting 15, bearing 16, axle 17 to which the plow-beams are secured, fulcrum-block 18 and adjusting-block 19, are all parts of 40 the original plow frame.

In the old arrangement of parts the lever 4 extended only to and was pivoted at 7 and when raised or lowered moved only link 12 fulcrumed on block 18 and could raise 45 or lower the plows only about an inch until the block 18 was removed, readjusted to the height desired and again secured to block 19.

My invention consists of angular arm 8 integral with lever 4 which is pivoted at 7 50 to the standard of ratchet segment 5, link 11 pivoted at 10 to said arm 8, link 20 pivoted at 9 to said link 11 and at 14 to

casting 15 which is firmly secured by sleeve connection 16 to axle 17 to which the plow-beams are attached. The plows having been 55 lowered by means of the lever (not shown) on the opposite side of the machine, the depth of the plows in the soil is adjusted by throwing the lever 4 forward or backward as desired. By drawing the lever backward 60 the link 12 is raised clear of block 18 and link 20 is thrown down till it fulcrums on said block and forces it downward and, at the same time, casting 15 is thrown upward; thus with the assistance of lifting spring 21 65 secured to the standard of ratchet segment 5 and to extension 22 of casting 15 secured to axle 17, raising the plows to a higher level in the soil and by throwing said lever 4 forward the plows are allowed to settle 70 deeper into the soil.

The fulcrum block 18 in conjunction with adjusting block 19 may still be used as heretofore to secure a greater range of adjustment of the plows; but with my device the occasion for readjustment of said block 18 is made less frequent. In fact the adjustment of said block 18 once made when starting to plow, no change thereof is likely to be found necessary, because with my device the angular arm 8 coupled by link 11 to link 20 which is fulcrumed on said block 18 and pivoted to casting 15 gives a greater range of adjustment of the plows and a greater leverage, enabling the operator by 80 means of lever 4 to raise and lower the plows in the soil as required in the field even tho the soil be tenacious and resisting.

My device does not and is not intended to raise the plows out of the ground. That 90 is done by means of the lever (not shown) provided therefor on the opposite side of the tractor.

Having thus described my invention what I claim as new and desire to secure by Letters Patent is—

The combination with a traction plow having a plow beam operating axle, of means for regulating the depth of the plowing elements of the plow in the soil, including a ratchet segment having a standard, a lever having an angularly extending arm on the lower end thereof and pivoted at the angle thus formed to the standard of the ratchet

segment, a link having its lower end pivotally connected to the free end of said arm, a fulcrum block in conjunction with an adjusting block, a second link having one end pivotally connected to the upper end of said first named link and cooperating with said fulcrum block, said second link having the

opposite end thereof pivotally secured to the axle.

ERNEST H. CARLSON.
